TELEGRAPH KEY

Ralph M. Heintz, Palo Alto, Calif., assignor to
Heintz & Kaufman, Ltd., San Francisco, Calif.,
a corporation of Nevada

Application May 1, 1933, Serial No. 668,778

3 Claims. (Cl. 178—101)

My invention relates to telegraph keys and more particularly to a key adapted for panel mounting, or for use on such panels which are exposed to the elements, the contact points actuated by the key being protected from rain, fog, snow or other moisture.

Among the objects of my invention are: to provide a light and sturdy telegraph key adapted for airplane use; to provide a telegraph key which may be conveniently mounted on a vertical panel or bulkhead; to provide a telegraph key which, when mounted on a panel exposed to the elements, will have its contacts protected from moisture; and to provide a simple efficient multiple contact telegraph key.

Other objects of my invention will be apparent or will be specifically pointed out in the description forming a part of this specification, but I do not limit myself to the embodiment of my invention herein described, as various forms may be adopted within the scope of the claims.

The advantages of my invention can be most readily understood by a description of the drawing accompanying and forming a part of this specification, of which:

Figure 1 is a top view in elevation of a preferred form of key adapted to be applied to a vertical panel.

Figure 2 is a side view in elevation of the device.

Figure 3 is a sectional view taken along the line 3—3 in Figure 1, the key being shown fastened to a panel.

Figure 4 is an elevational view of the device as seen from the front.

Figure 5 is an elevational view taken from the rear.

In the preferred embodiment illustrated in the drawing, a metal cup, preferably of aluminum or aluminum alloy, is formed with a hollow body portion 1 and a rim 2. The outer face 4 of the rim is adapted to fit a panel or bulkhead 5 as shown in Figures 2 and 3, the rim being bored to form threaded holes 6. The panel and rim may then be fastened together with panel screws 7. It is also desirable to cut an aperture in the panel as large or slightly larger than the cross section of the hollow in the cup body, to allow the passage of the operating arm, which will be later described.

A metal shaft 9 passes through opposite walls of the hollow body portion, and through a bearing 10 in the end of an operating arm having an enclosed portion 11 extending out past the rim and thereafter changing direction to form an oblique angle with the rim and attached to the panel.

The portion outside of the rim after the arm has changed direction, may be termed the operating arm extension 12, which terminates at its distal end in an operating button 14, similar to those used on telegraph keys in common use.

I prefer to mill or otherwise form a flat surface 15 parallel with the outer face 4, on the operating arm at the point where the arm changes direction, drill through the enclosed portion 11 of the arm to the shaft 9, tap the hole and insert 63 therein a set screw 16 having a point 17 engaging the shaft, and an exposed slotted head 19. I may thereby adjust the relative position of the arm on the shaft, and lock the two to cause rotary motion of the shaft to take place upon actuation 70 of the operating arm.

The two ends 20—20 of the shaft which extend outside the cup are preferably slotted and a flat contact spring 21 inserted in each and held in place by pins 22. These springs, of phosphor bronze or similar material, extend in both directions at right angles to the shaft, and substantially parallel to the outer face 4. I have shown these springs extending both ways for substantially equal distances, but the relation 80 of distances on each side of the shaft may be changed to suit conditions of use.

Inserted in the ends of each contact spring are contact points 24, preferably four in all.

The bottom outside face 25 of the cup is formed 83 with a slot 26 in which is set the crossbar 27 of an H-shaped piece of insulating material 29, held in place by a clamp plate 30 tightened by a clamp screw 31 passing through the clamp plate and insulating crossbar 27 and extending 90 into the bottom of the hollow body portion. The insulating material cannot turn, as its edges are held by the sides of the slot 26.

The end extensions 32 of the H terminate below the ends of the contact springs 21 and carry 95 stationary contacts 34 extending toward the contact points on the contact springs. The contacts 34 are held in place by nuts 35 which also hold connection lugs 36 in place.

The cooperating sets of contact points and 100 contacts are so located that at one position of the operating arm the upper set of contact points make contact with the upper set of stationary contacts, and the remaining connections are broken, while at another position of the arm the 105 reverse will take place.

I prefer, however, to maintain the upper connections by means of force exerted by a spring 37 attached at one end to the shaft 9 and at the other to the H-shaped piece of insulating 110

material. One set of connections are thus made at all times the key is not operated, those connections being broken, and a second set made when the button 14 is depressed, the key returning to the original position, and connections, when released.

No adjustments are shown on the key illustrated, as bending the contact springs will allow any necessary adjustments to be made. Neither 10 is there any stop necessary, as the operating arm will hit the cup rim if depressed too far, the give in the contact springs preventing damage up to that point.

The key as illustrated is particularly adapted 15 to be mounted on the instrument panel of an open cockpit airplane, fully exposed to the weather. The angle of the operating arm enables the key to be readily actuated, even with gloves. The key is water and moisture proof 20 when applied to such a panel, as when mounted in a vertical position as described, water will run out of the hollow body portion, the shaft holes being well above the bottom (as mounted) of the cavity. The electrical contacts are behind the 25 panel, and if desired may be enclosed in a separate covering to prevent sparks from the contact points igniting gasoline vapor.

The form of key shown has been proved practical for airplane use as described, particularly as 30 there usually are no convenient horizontal surfaces upon which to mount a key of the ordinary type, the instrument panel however, being readily reached by the pilot. The key as described is also ideally adapted to be inserted in 35 various circuits of a tube transmitter to provide a break-in system, all of the movable contacts and the operating arm being at ground potential.

I claim:

1. A telegraph key comprising in combination, 40 a metal cup having a hollow body portion and a rim, said rim having a face adapted to be fastened to a panel, a shaft passing through the opposite walls of said cup, an operating arm mounted on said shaft within said cup, said

45

arm extending coaxially with said body portion to a level adjacent said face and thereafter changing direction to form an oblique angle with said face, and contacts mounted on said shaft outside of said cup.

80

2. A telegraph key comprising in combination, a metal cup having a hollow body portion and a rim, said rim having a face adapted to be fastened to a panel, a shaft passing through the opposite wall of said cup, an operating arm mounted on said shaft within said cup, said arm extending coaxially with said body portion to a level adjacent said face and thereafter changing direction to form an oblique angle with said face, contacts movable by the motion of said arm mounted on said shaft outside of said cup, an insulating member mounted on the bottom of said cup, and stationary contacts carried by said insulating member to cooperate with said movable contacts for making or breaking electrical currents.

85

3. A telegraph key comprising in combination, a metal cup having a hollow body portion and a rim, said rim having a face adapted to be fastened to a panel, a shaft passing through the opposite walls of said cup, an operating arm mounted on said shaft within said cup, said arm extending coaxially with said body portion to a level adjacent said face and thereafter changing direction to form an oblique angle with said face, contacts movable by the motion of said arm mounted on said shaft outside of said cup, an insulating member mounted on the bottom of said cup, and stationary contacts carried by said insulating member to cooperate with said movable contacts for making or breaking electrical currents.

90

3. A telegraph key comprising in combination, a metal cup having a hollow body portion and a rim, said rim having a face adapted to be fastened to a panel, a shaft passing through the opposite walls of said cup, an operating arm mounted on said shaft within said cup, said arm extending coaxially with said body portion to a level adjacent said face and thereafter changing direction to form an oblique angle with said face, a resilient member fastened to one end of said shaft, said resilient member extending on each side of said shaft at right angles thereto, a contact point on each end of said resilient member, an insulating member mounted on the bottom of said cup, stationary contacts carried by said insulating member to cooperate with each of said contact points for making or breaking electrical currents, and means for resiliently 105 maintaining one of said contact points and one of said stationary contacts in contact.
